[57] **CLAIM**

The ornamental design for an air compressor, substantially as shown.

DESCRIPTION

FIG. 1 is a perspective view taken from top, front and left end of an air compressor showing our new design; FIG. 2 is a front elevational view thereof; FIG. 3 is a top plan view thereof; FIG. 4 is a right end elevational view thereof; FIG. 5 is a rear elevational view thereof; FIG. 6 is a perspective view similar to FIG. 1, but with the cover in an open position; FIG. 7 is a front elevational view thereof with the cover removed for convenience of illustration; FIG. 8 is a top plan view of FIG. 7; FIG. 9 is a right end elevational view of FIG. 7; FIG. 10 is a left end elevational view of FIG. 7; and FIG. 11 is a rear elevational view of FIG. 7.
